UNITED STATES PATENT OFFICE

JOHN ROCCIOLA, OF LODI, NEW JERSEY

EMBALMING PUMP

Application filed February 5, 1930. Serial No. 426,145.

This invention relates to pumps especially designed for embalmers' use, an object being to provide an electrically driven pump by means of which embalming fluid may be ejected under sufficient pressure to be thoroughly distributed throughout the body of a corpse with a minimum number of injections.

Another object of the invention is the provision of a device of the above character which includes a motor driven pump and a fan for cooling the pump, with the motor, fan and pump constructed as a unit so that they may be conveniently supported, with means to support the unit to absorb vibration and noise, so that the device will operate quietly, which is essential in devices for this purpose.

Another object of the invention is the provision of means for conveniently and accurately controlling the speed of the motor and operation of the pump so that pressure of the fluid may be accurately controlled.

With the above and other objects in view, the invention further includes the following novel features and details of construction, to be hereinafter more fully described, illustrated in the accompanying drawings and pointed out in the appended claim.

30 In the drawings:—

Figure 1 is an elevation of the invention.

Figure 2 is a top plan view.

Figure 3 is an elevation at right angles to

Figure 1.

35 Figure 4 is an enlarged front view of a slightly different form of the invention, parts being broken away and shown in section.

Figure 5 is a fragmentary top plan view of the subject matter of Figure 4.

40 Referring to the drawings in detail wherein like characters of reference denote corresponding parts, the reference character 10 indicates a base which may be in the form of a hollow platform, while 11 indicates a yoke-like support which is secured to and rises from the base.

The invention includes a motor, the housing of which is indicated at 12, while the shaft of the motor is indicated at 13. Arranged 50 within the motor housing and mounted upon

the shaft 13 are fan blades 14, while positioned within the reduced end of the housing is a rotary pump 15 which is also mounted upon the shaft 13. The fan acts to cool the pump and to assist in this cooling operation, the housing is provided with a plurality of radially disposed veins or fins 16.

As it will be apparent, the motor, fan and pump are constructed as a single unit and in order to support this unit from the base 10 and support 11, the housing 12 carries a hanger loop 17 which engages over the yoke-like support 11. This loop will also serve as a handle when the unit is detached from the support. This removal of the unit may be effected by detaching the support from the base.

The pump is provided with an inlet 18 which may be connected by means of a tube 19 with a source of fluid supply, while an outlet 20 provides means for connection with a discharge tube 21. A pressure gauge 22 is interposed between this tube and the outlet 20, so that the pressure of the pump may be indicated.

The base 10 carries lugs 23 and 24 for conductors 25 and 26 to provide means for supplying current to the motor. A rheostat 27, mounted upon the base is connected in circuit with the motor so as to regulate the supply of current thereto. A switch 28 is also included in the motor circuit.

In order to reduce vibration and eliminate noise, the unit which includes the motor, the fan and the pump, is connected with the support 11 by means of springs 29, while a spring 30 connects the unit with the base 10. The spring 30 is adjustably secured to the unit and for this purpose the latter is provided with a flange 31 having spaced apertures 32 therein to receive the end of the spring, so that the unit may be yieldingly mounted and properly balanced. A cushion effect is thus provided so that noise and vibration will be reduced to a minimum.

In Figures 4 and 5 of the drawings, the motor housing 12 carries a pump 32 of the reciprocating type. This pump includes a cylinder 33 having a check valve controlled inlet 34 and a check valve controlled outlet

35. The piston 36 operates within this cylinder and this piston is connected by means of a rod 37 with a crank arm 38 which is fast upon the motor shaft 13. The crank arm operates within the housing 39 which is provided with screen covered openings 40 so as to provide cooling means, while the cylinder 33 is provided with cooling fins 41.

10 The invention is susceptible of various changes in its form, proportions and minor details of construction and the right is herein reserved to make such changes as properly fall within the scope of the appended claim.

15 Having described the invention what is claimed is:—

20 In an electrically operated pump, a base, a yoke-like support secured to and rising from the base, a motor including a housing positioned within the yoke above the base, a hanger loop secured to the motor housing and engaging over the yoke, springs connecting the housing and yoke and housing and base to yieldingly hold the motor housing in horizontal position, a motor driven fan included in said housing, a motor driven pump also included in said housing, means to connect the pump with a source of fluid supply, and a discharge outlet for the pump.

JOHN ROCCIOLA.
